UNITED STATES PATENT OFFICE.

JETHRO L. MACY, OF DES MOINES, IOWA.

DESIGN FOR A MOISTURE-TANK FOR INCUBATORS, &c.

SPECIFICATION forming part of Design No. 30,900, dated May 30, 1899.

Application filed April 17, 1899. Serial No. 713,416. Term of patent 14 years.

To all whom it may concern:

Be it known that I, JETHRO L. MACY, a citizen of the United States of America, and a resident of Des Moines, Polk county, Iowa, have invented a certain new and useful Design for a Moisture-Tank for Incubators and Brooders, of which the following is a specification.

The object of this invention is to produce a new and original design for a moisture-tank; and my invention consists of the design hereinafter set forth, pointed out in my claim, and illustrated by the accompanying drawing, which is a perspective showing the complete design.

In the design as illustrated the numeral 10 designates an annular tube circular in cross-section and open at its top. An annular tube 12 is mounted within and concentric of the tube 10 and is of approximately the same length as said tube 10. A rectangular flat plate 13 is mounted horizontally on and fixed to the top of the tube 10, and an opening is

formed in said plate at and of the same size and shape as the cross-section or top of said tube. Side pieces 14 15 are formed on and extended upwardly at right angles to the side margins of the plate 13, and end pieces 16 17 are formed on and extended upwardly at right angles to the end margins of said plate 13. The side pieces 14 15 are provided with outwardly-extending horizontal flanges 17 18 on their upper margins, and the end piece 16 also is provided with a horizontal outwardly-extending flange 19 on its upper margin.

I claim as my invention—

The design for a moisture-tank for incubators and brooders, substantially as herein shown and described.

Signed by me, at Des Moines, Iowa, this 9th day of February, 1899.

JETHRO L. MACY.
